No. 36,495.

Patented August 18, 1903.

UNITED STATES PATENT OFFICE.

KENNETH MELROSE, OF SAN FRANCISCO, CALIFORNIA.

DESIGN FOR A BADGE.

SPECIFICATION forming part of Design No. 36,495, dated August 18, 1903.

Application filed July 1, 1903. Serial No. 163,980. Term of patent 3½ years.

To all whom it may concern:

Be it known that I, KENNETH MELROSE, a citizen of the United States, residing at San Francisco, in the county of San Francisco and State of California, have invented a certain new, original, and ornamental Design for Badges, of which the following is a specification.

In the accompanying drawing the figure is to a front view of a badge, showing my design.

What I claim as new, and desire to secure by Letters Patent, is—

The ornamental design for a badge as herein shown.

In witness whereof I have hereunto set my hand in the presence of two subscribing witnesses.

KENNETH MELROSE.
